FIG. 1

FIG. 2

FIG. 3

FIG. 4

FIG. 5

FIG. 1 is a perspective view of a valve receiving tubing fitting showing my new design;

FIG. 2 is an end elevational view thereof, the opposite end being the same as the end shown;

FIG. 3 is an end elevational view of a modified form of the valve receiving tubing fitting shown in FIG. 1, the opposite end being the same as the end shown;

FIG. 4 is an end elevational view of a second modified form of the valve receiving tubing fitting shown in FIG. 1, the opposite end being the same as the end shown;

FIG. 5 is an end elevational view of a third modified form of the valve receiving tubing fitting shown in FIG. 1, the opposite end being the same as the end shown;

FIG. 6 is a side elevational view of FIG. 5;

FIG. 7 is a side elevational view of the fittings shown in FIGS. 2, 3 and 4;

FIG. 8 is a top plan view of the fittings shown in FIGS. 2 and 3;

FIG. 9 is a top plan view of FIG. 4;

FIG. 10 is a top plan view of FIG. 5; and

FIG. 11 is a bottom plan view of the fittings shown in FIGS. 2, 3, 4 and 5.

The broken line representation of a tube in FIGS. 1 through 5 and the broken line representation of a valve in FIGS. 2 through 5 are for purposes of illustration only.

I claim:

The ornamental design for a valve receiving tubing fitting, substantially as shown and described.
